RAZOR-BLADE HOLDER

Harry M. Dahl, Sr., Yoakum, Tex.

Application August 29, 1934, Serial No. 741,976

3 Claims. (Cl. 30—25)

My invention relates to an improved holder for razor blades and has for its object to provide a holder which is adapted to hold various types of safety razor blades in a manner to permit strapping of the blades.

A further object of the invention is to provide a holder having a pair of jaws movable relative to one another, adapted to receive a blade therebetween and a clamping bar for locking the blade in the jaws to prevent accidental displacement of the blade while stropping the same.

Another object of the invention is to provide a device of the above-mentioned character which is simple and durable in construction, reliable and efficient in use and inexpensive to manufacture.

Other objects and advantages of the invention will be apparent during the course of the following description.

In the accompanying drawing, forming a part of this specification and in which like numerals are employed to designate like parts throughout the same,

Fig. 1 is a top plan view of the holder showing a double edge razor blade secured therein,

Fig. 2 is a bottom plan view of the same,

Fig. 3 is a side elevation view of the same with the clamping bar in a raised position, and,

Fig. 4 is a top plan view of the holder showing a single edge razor blade secured therein.

In the drawing, wherein for the purpose of illustration, I have shown a preferred embodiment of my invention, the numerals 5 and 6 denote a pair of jaws constructed from elongated metal strips disposed in superimposed relation and attached to one end of the jaws is a handle 7. The jaws adjacent the handle are fixedly secured together by rivet 8 and the free ends of the jaws are freely movable relative to one another so that a razor blade 9 may be inserted therebetween.

The jaws are relatively narrow so that when the blade is positioned between the jaws the cutting edges of the blade will project beyond the side edges of the jaws. The free ends of both the jaws are bifurcated, as at 10 and 11, to receive the head

12 of the clamping bar 13 which is adapted to lie on top of the jaw 5 when in locking position. The head 12 is off-set from the bar 13 and the connecting portion 14 between the bar and head is reduced to engage in the bifurcations 10 and 11 of the jaws, whereby the head 12 engages the underside of the jaw 6, securing one end of the clamping bar and jaws together. The opposite end of the clamping bar 13 is provided with a longitudinal slot 15, adapted to be engaged by the pin 16 extending upwardly from the jaw 5 and

a sleeve 17 slidably mounted on the jaws is movable over the end of the clamping bar securely locking the bar against displacement. The pin 16 when engaged in the slot 15 limits the longitudinal movement of the locking bar, so as to prevent the head 12 from becoming dis-engaged and the sleeve 17 holds the bar 13 and jaws together so the pin 16 will not become dis-engaged from the slot 15. When the sleeve 17 is moved from engagement with the clamping bar it is supported by the raised portion 18 on the jaw 5 on a plane with the clamping bar for ready engagement therewith.

In use, various types of razor blades may be held by the holder for stropping. The improved type of double edge blade having the central longitudinal slot is secured in the holder by first inserting the head 12 of the clamping bar 13 through the slot of the blade, then inserting the blade between the jaws 5 and 6 and moving it longitudinally of the jaws until the connecting portion 14 between the head 12 and bar 13 engages in the bifurcations 10 and 11 of the jaws, after which the sleeve 17 is moved into engagement with the inner end of the clamping bar 13 securely locking it in its clamped position. Single edge blades and double edge blades of the old type are secured in the holder by first inserting the blade between the jaws and then engaging the head 12 of the clamping bar 13 with the bifurcations 10 and 11, after which the sleeve 17 is moved into engagement with the free end of the clamping bar. While the holder is primarily adapted to hold razor blades for stropping it is apparent that it may also be used for holding razor blades in various positions for use as a scraper, cutting seams and other purposes for which razor blades are now used.

It is to be understood that the form of my invention herewith shown and described is to be taken as a preferred example of the same and that certain changes in the shape, size and arrangement of the parts may be made without departing from the spirit of the invention or the scope of the subjoined claims.

Having thus described my invention, I claim:

1. A razor blade holder comprising a pair of superimposed jaws movable relative to one another and adapted to hold a blade therebetween, the free ends of said jaws being bifurcated, a clamping bar having a head at one end adapted to engage in the bifurcations at the free ends of said jaws and means for securing the opposite end of said clamping bar to said jaws.

2. A razor blade holder comprising a pair of

- superimposed jaws movable relative to one another and adapted to hold a blade therebetween, the free ends of said jaws being bifurcated, a clamping bar extending longitudinally of said jaws having an off-set head at one end adapted to engage in the bifurcations of said jaws, a sleeve slidably mounted on said jaws movable to engage over the opposite end of said clamping bar.
5. A razor blade holder comprising a pair of relatively narrow elongated jaws fixedly secured together at one end and having their free ends movable relative to one another adapted to hold
- a blade therebetween, the free ends of said jaws having bifurcations therein, a clamping bar extending longitudinally of said jaws and adapted to rest on top of one of the jaws, said bar having an off-set head at one end adapted to engage in the bifurcations of said jaws, a pin extending upwardly from one of said jaws for engagement with a slot in the opposite end of said clamping bar, and a sleeve slidably mounted on said jaws movable to engage over the end of said clamping bar to lock the bar in clamping position.
10. A razor blade holder comprising a pair of relatively narrow elongated jaws fixedly secured together at one end and having their free ends movable relative to one another adapted to hold
